(57) **CLAIM**

The ornamental design for a short plate for a modular truck bed rack system, as shown and described.

DESCRIPTION

FIG. 1 is a front view of a short plate for a modular truck bed rack system, according to our new design;

FIG. 2 is a left side view thereof;

FIG. 3 is a three-quarters front perspective view thereof;

FIG. 4 is a top view thereof;

FIG. 5 is a three-quarters back perspective view thereof; and,

FIG. 6 is a bottom view thereof.

The dashed broken lines in the drawings show portions of the short plate for a modular truck bed rack system that form no part of the claimed design.

1 Claim, 3 Drawing Sheets
